UNITED STATES PATENT OFFICE

JOSEPH A. O'NEILL, OF NEW YORK, N. Y.

AUTOMATIC DISK RECORD PLAYER

Application filed June 17, 1925. Serial No. 37,667.

This invention relates to improvements in phonographs and other record playing mechanisms, and has for its object to provide a machine of the above named class which will automatically play and successively interchange a plurality of records without attention.

A feature of my present improvements is to provide a cabinet of comparatively compact form having three compartments, one to contain the operating mechanism, while the other two are in the form of "wells" to receive a multiplicity of trays or carriers on which the disk records are supported, one well or compartment, the one nearest the record turntable, being employed to receive old, or used records which are periodically lowered into said well by successive mechanical control step movements which occur just after each played record has been lifted from the turntable and conveyed across and over the uppermost empty tray and dropped thereon, after which a new, or unplayed record, with its supporting tray, may be moved across from the opposite well onto and over the uppermost played record and its tray, from which position it is in turn lifted and moved across and over the turntable and dropped into position for playing, and this operation is repeated over and over again until all the records contained in the cabinet are played, after which said records may be turned over or reversed, when the automatic mechanism may be again started and by my improved construction, an entire program of entertainment, either in dance, song, or other music may be rendered without attention to the mechanism.

A further feature of my present invention is the provision of means for automatically changing the needle or stylus after each record has been played to insure perfect tones and to preserve the records.

A still further feature of my invention is to provide a novel construction whereby when certain parts are disconnected, the machine may be employed to play disk records in the usual way, that is, the records may be supplied to the turntable and removed therefrom and the tone arm manipulated by hand.

In the accompanying drawings I have illustrated a preferred embodiment of the invention, but the construction shown therein is to be understood as illustrative only, and not as defining the limits of the invention.

Corresponding reference characters are employed to designate like parts throughout the several views, in which:—

Fig. 1 is a plan view of my improved automatic disk record playing machine.

Fig. 2 is a front elevation thereof, partly in section and with parts omitted.

Fig. 3 is an enlarged elevation, partly in section, of the record tray wells and showing the means for lowering the trays in one well and elevating them in the other.

Fig. 4 is a cross section on the line 4—4 of Fig. 3.

Fig. 5 is a fragmentary section taken on the line 5—5 of Fig. 3.

Fig. 6 is another fragmentary section on the line 6—6 of Fig. 3.

Fig. 7 is a perspective of one of the disk record supporting trays.

Fig. 8 is a detail vertical section showing a conveyor arm and its co-ordinating parts.

Fig. 9 is a horizontal section on the line 9—9 of Fig. 8.

Fig. 10 is a vertical section on the line 10—10 of Fig. 8.

Fig. 11 is a vertical section on the line 11—11 of Fig. 8.

Fig. 12 is a vertical section on the line 12—12 of Fig. 8.

Fig. 12a, is a detail view of a tripper cam and associated parts.

Fig. 13 is an enlarged detail section on the line 13—13 of Fig. 8 showing a pair of pickup hooks in the normal raised position.

Fig. 14 is a similar section showing the hooks depressed and engaging a disk record.

Fig. 15 is a detail sectional elevation showing the tone arm and stylus control means.

Fig. 16 is a vertical section on the line 16—16 of Fig. 15.

Figs. 17 and 18 are views similar to Fig. 15 with the parts in different positions.

Fig. 19 is a sectional elevation showing the tone arm with parts of my invention attached thereto.

Fig. 20 is a perspective of a detail of the construction.

Fig. 21 is a detail showing means for giving the star wheel shafts a quarter rotation.

5 Fig. 22 is a perspective showing means for supplying a fresh needle to the sound box at each outward swing of the tone arm.

Fig. 23 is a plan view of the same, this position being at the moment the spring jaws 10 carry away a new needle.

Fig. 24 is a diagrammatic view showing the method of forcing out a used needle and taking away a new one.

15 Fig. 25 is a detail edge view of a portion of the needle disk.

Fig. 26 is a detail plan view showing a trip mechanism governed by the tone arm to actuate a power clutch controlling a cam shaft.

20 Fig. 27 is a horizontal section taken below the top plate on which the mechanism shown in Fig. 26 is mounted.

Fig. 28 is a detail perspective of a trip arm employed.

25 Fig. 29 is a side view of the trip mechanism shown in Fig. 26.

Fig. 30 is a perspective of a tripper device employed.

In describing my invention I provide a cabinet A of rectangular form, divided in 30 three separate compartments, the larger one B occupying one end of the cabinet and extending entirely around the other compartments C and D which latter, for the purpose of this description, I will term "wells" which 35 serve to receive and guide a plurality of disk records 10, each supported on a tray or carrier 11.

At the top, the cabinet A supports the usual tone arm E communicating with the 40 usual internal outlet horn F see Fig. 16.

In the construction shown, the compartment B contains most of the operating mechanism including a motor 12, connected by wiring to a snap switch 13 on top of the cabinet 45 net, the normally open circuit being closed when a brake shoe 14 is withdrawn from peripheral contact with the record turntable 15.

The motor is preferably worm geared as at 16 to a short shaft 17 for driving the record turntable shaft 18 through bevel gears 19 20, shown clearly in Fig. 26.

55 Shaft 17 extends backwardly and carries a male clutch member 21 co-acting with a female companion member 22 on a cam shaft 23, carrying a number of cams to be presently described.

A conveyor arm 24 is mounted to oscillate over the cabinet and is constituted by a housing 25 having a cross plate 26 provided with 60 an integral squared pin 27 received in a corresponding bore 28 in the upper end of a vertical shaft 29, mounted to rotate in a bearing 30 having a flange 31 which is engaged by a turntable catch 32 to prevent arm 24 65 from lifting.

The lower end of shaft 29 is journaled in a bracket 33, and has a fixed short arm 34 connected by a link 35 to a lever 36, swinging from a bracket 37 and having a roller 38 operating in a groove 39 of a cam 40.

70 A pair of companion levers 41 are loosely carried on a cross pin 42 passing into the sides of housing 25 of arm 24 and, as shown in Fig. 9 of the drawings, normally have their rear ends abutting and their forward ends divergently separated, this position being maintained by a spring 43 the under adjacent corners of the rear ends of said levers being beveled as at 44 see Fig. 11 to form an inverted V shaped guide for one of 80 a pair of wedged spreaders 45 on a cross head 46 forming part of a vertical bar 47 slideable in a guide 48 and provided at the bottom thereof with a roller 49, working in a slot 50, in a horizontally reciprocating plate 51 85 carried at one end in a guide 52 and supported at the opposite end by a fork 53 which straddles the cam shaft 23 and rests thereon, said slot being cut at an angle to the length of members 47 and 51 to cam 90 the roller 49 upward when the plate 51 is moved to the left in Fig. 11.

The plate 51 also carries a roller 54 to operate in a groove 55 of a record releasing cam 56, which only operates to raise the 95 wedged spreaders 45 to release a record at the end of the delivery swing of the conveyor arm 24 in either direction.

To depress the front hooked ends of levers 41 to engage a record, I employ a lifting head 100 57 lying just below the rear ends of said levers, which is formed integral with a vertical bar 58 slideable in a guide 59 and provided with a roller 60 at the lower end working in a slot 61 formed in a reciprocating bar 62 said slot being cut at an angle with respect to the length of the bars 58 and 62 and acting to cam the bar 59 and head 57 upward and tilt the rear ends of said levers on pin 42 against the action of a spring 68 110 when bar 62 is moved to the left in Fig. 10.

Bar 62 rests in a guide bracket 63 at one end and has a fork 64 at the opposite end, and also carries a roller 65, to engage the slot 66 of a record pickup cam 67 and the fork 115 straddles cam shaft 23 and rests thereon.

The front separated ends of levers 41 have downward extensions 68 tapered at the terminals as at 69 and shouldered as at 70 to form hooks adapted to pass through the record aperture 71 and engage the underface thereof as shown in Fig. 14 to lift and convey the record in the operation of the machine.

When the hooks are depressed to pick up a record, the centering post 72 according to 125 my invention, is forced down into a bore 73 in the turntable shaft 18, against a spring 74, and its movement is restricted by a pin 75 working in a slot 76 see Fig. 19 and the bore 73 is enlarged at its top to form a cham- 130

ber 77 to allow the hooks to spread and engage the record after passing down through the aperture 71.

The automatic means for controlling the tone arm and its sound box may be described as follows:—

A bracket 78 is made fast to the cabinet as at 79 and has side guides 80 in which a cage 81 is movable up and down. The cage receives a block 82 which is slidable therein and which has a circular lug 83 on one side and a pin 84 threaded into the top thereof, which extends upwardly through a slot 85 in the top of the cage and through a corresponding slot 86 in the cabinet, and at the top of said pin is a nut 87 bearing on a lever 88 to be presently described.

The bracket 78 has an arm 89 in which is pivoted a cam lever 90 connected to the underside of cage 81 between apertured ears 91 by a cross pin 92 and on the other end of lever 90 is a roller 93 bearing on a cam 94 which operates to force the said cage and block 82 downwardly to the position shown in Fig. 17 to raise the stylus away from the record as hereinafter described.

The bottom of the bracket 78 is formed with a guideway 95 to receive a slide plate 96 formed with a vertical fork 97, straddling the lug 83, a horizontal fork 98 straddling the cam shaft 23 and a lug 99 and also carries a roller 100 co-acting with a cam 101 which acts to force block 82 to the further end of cage 81 as shown in Fig. 18.

Lever 88 has a slot 102 at its inner free end, in which the pin 84 operates and is made in two parts 103 and 104 joined by a knuckle joint 105. The part 104 has an aperture 106 in which a pin 107 is fixed, said pin being passed through spaced ears 108 to support the part 109 of a two part lever 110 which parts are joined by a knuckle joint 111, the outer part 112 of this lever is apertured to hold a link 113 connected with an eye 114 on the sound box 115.

The sound box, see Fig. 22 has a fixed jaw 116 and a co-acting hinged jaw 117 which is backed by a spring 118 to yieldingly support, in one direction, a needle or stylus 120 confined in companion grooves 119 formed in the adjacent faces of said jaws.

The automatic means for supplying a fresh needle or stylus to the sound box after each succeeding record is played may be described as follows:—

A needle holding disk 121 is mounted to rotate on a post 122 at an angle to the top of the cabinet, and is provided with peripheral sockets 123 to receive new needles 120a which are held in said sockets by delicate springs 124 and said disk also carries a ratchet 125 on its underface which is engaged by a spring metal stop arm 126 and a push dog 127 pivotally carried on a trip arm 128 back pressed by a spring 129, and the said trip arm

pivots about the post 122, with its free end 130, in the path of movement of the jaw 116 which contacts therewith, to rotate the disk one step, equal to the distance between sockets to present a new needle in position, just as the tone arm starts to swing back or inwardly after the said jaws have taken away a fresh needle.

To discard a used needle at near the end of the outward movement of the tone arm, I employ an ejector plate 131 unitary with a support 132 attached to the cabinet, said plate being positioned to engage the beveled faces 133 of jaws 116 and 117 to separate them and force out the used needle, said plate being elongated as shown, to hold the hinged jaw open until the grooves 119 of the jaws are in vertical alinement with the nearest new needle 120 held by disk 121 when said jaws will ride off the said plate, and close over the aforesaid new needle, and at this moment, in the operation of the machine, the roller 93 on lever 90 will ride down onto a lower face 134 of cam 94 after having just passed over the high face 135 thereof, thus permitting the sound box 115 by the action of gravity, to drop slightly on its pivot and withdraw the new needle from its socket, and when in this plane or position, the jaws and the new needle therein, in the return or inward movement of the tone arm and its sound box to the playing position, will have clearance past the ejector plate support through a loop or bend 136a, formed therein. It is also when in this position, the upper jaw 116 engages the trip lever 128 at the beginning of the inward movement of the tone arm, to rotate the needle disk one step, as will be readily understood.

The automatic means for lowering the played records into their well or compartment and for simultaneously raising the unplayed records one step in their well, to be successively presented for transfer to the playing turntable, may be described as follows:—

Journalled in bearings 136 attached to the outer walls of the wells or compartments C, and D, are two opposite pairs of revoluble shafts 137 and 138 which have star wheels 139 and 140 fixed thereto and rotated in step movements by a trip wheel 141 having four equi-distant spurs 142 positioned so that one spur normally lies in the path of travel of a trip lug 143 on the peripheral edge of a cam 144, to be hereinafter described.

Each pair of shafts 137, 138 are geared one to the other by intermeshed pinions 145 and the shafts, in pairs, at opposite sides of the wells are given reverse rotation by a crossed chain 146 travelling over sprockets 147 the direction of rotation being indicated by the arrows in Fig. 4, 5, and 6.

The opposite sides of the compartment D are cut out as at 148 to receive spring pressed dogs 149 each having a nose 150 projecting into the compartment to support the succe-

sive trays 11, therein as they go upward, to leave clearance for the next incoming tray from compartment C, said nose being formed with a beveled face 151 against which the lower tray impinges when carried upward by star wheels 140 to force the nose out, and after the tray passes, the nose is forced in under the edge thereof as shown in Fig. 5 by a spring 153.

10 The record supporting trays 11 are preferably of sheet metal each comprising a flat body portion 154 having a circular depressed portion 155 and a central aperture 156. The end edges are curled as at 157 for strength, 15 the side edges being bent down to form rests 158 and inwardly to provide rounded resting faces 159.

15 The means for shifting the bottom tray in well C to well D and the topmost tray on well 20 D over onto the played records in well C simultaneously, may be described as follows:—

20 The cam 144 fixed to shaft 23 has a groove 161 in which a roller 162 on a reciprocating 25 rod 163 operates, see Fig. 1, said rod being attached to an arm 164 fast on vertical shaft 165 journalled in bearings 166, and carrying at the bottom a shift arm 167 and a shorter oppositely directed arm 168 connected by a 30 link 169 to a similar arm 170 on a vertically arranged shaft 171 mounted in bearings 172 and fixed to its top portion is another shift arm 173 provided with a depending finger 173a which engages the side of each successive tray 11 to push them across from well D over and onto the trays and records in well C, and at a predetermined time in the 35 operation of the machine, the cam 144 operates the rod 163 to impart opposite swinging 40 movements to the shift arms to simultaneously transfer or shift a tray from well C to D at the bottom and one from D to C at the top, as hereinbefore described.

45 The tripping mechanism for throwing in the clutch member 21, to operate shaft 23 through one revolution, at the end of the playing of a record, may be described as follows:—

50 A housing 174 fixed to the under face of the cabinet top (see Fig. 2), is provided to receive a frame 175 consisting of top and bottom plates 176 and 177, connected by posts 178.

55 An oscillating segmental gear 179 having an arm 180 is mounted on a pin 181 and meshes with a pinion 182 fixed to a large gear 183, which in turn is in mesh with an idler 184 meshed with a pinion 185 on a tripper shaft 186 supporting loosely a tripper 60 187 which rests on a leather washer 188 lying on a block 189 pinned to shaft 186 so that when said shaft is rotated, the tripper will be frictionally rotated therewith.

65 The tripper 187 is formed with a sleeve 190 and has spaced apertured ears 191 between

which a trip finger 192 is mounted to swing upwardly on a cross pin 193 said trip finger having a horizontal extension 194 and a depending lug 195 and the tripper is completed by a rigid finger 196 which extends outwardly in divergent relation to the hinged finger or extension as clearly shown in Fig. 30.

70 Mounted to loosely rotate on a shaft 197 is a trip arm 198 having a downwardly inclined portion 199 and a terminal lug 200 to rest against a fixed stop 201 on the bottom plate 177 of the frame 175 when the trip arm is in its set position as shown in Fig. 27. The said trip arm is preferably of sheet metal and has a head 202 with an apertured 80 side extension 203 and carries an upper lug 204 which bears against a leaf spring 205 and a lower trip lug 206 which is engaged by the extension finger of tripper 187 as will hereinafter appear.

85 The shaft 197 which is constantly rotated while a record is being played, has a single tooth gear 207 fixed to its top, which at every turn of said shaft, engages and imparts a step movement to a gear 207a mounted to freely 90 rotate between leather washers 208 mounted on a pin 209, said gear being held against racing by a spring dog 207b. Placed between the upper washer and a head on the pin 209 is a frictionally driven disk 210 having one 95 tooth or lug 211 which when turned in the direction of the arrow, will enter a recess 212 on one arm 213 of a lock member 214 freely mounted on a post 215 and the lock member also has a curved push 100 arm 216 and a stop finger 217 extending down through an opening in the top plate 176 of the frame 175 into the path of swinging movement of the pivoted extension finger 194 of tripper 187 under certain conditions.

105 At the bottom of shaft 197 is fixed a gear 218 which carries a trip lug 219 and is in mesh with an idler 220 meshing with a gear 221 on the drum shaft 18 to give constant rotation to lug 219 when a record is playing, for the purpose hereinafter set forth.

110 The extension 203 of arm 198 is connected by a link 222 to a shift lever 223 having a pin and groove connection as at 224 with the male clutch member 21, as clearly shown in Fig. 26 and the arm 180 of segmental gear 179 is connected by a link 225 to a bell crank lever 226 carried on the underside of the cabinet top A, its free arm being slotted at 227, to receive a pin 228 on the slide plate 96 of the tone arm control mechanism.

115 The segmental gear has a pin 229 which engages the push arm 216 when the finger 217 is in the unlocked position, or out of the path of swing of the tripper finger extension 194 to throw it into the locked position under certain conditions, and the arm 213 of the lock member is limited in its movements by pins 230. The swinging movement of tripper 187 120

is also limited by the shaft 231 of pinion 182 and a pin 233 extending down from the top plate 176 of frame 175.

To separate the clutch members 21, 23 and 5 reset the arm 198 of the trip mechanism, after shaft 23, has been driven a full turn, I provide a trip lug 234 on the female member 22 to engage a corresponding lug 235 on shift lever 223.

10 A spring 236 is provided on the bracket 78 with which the lug 99 on slide bar 96 contacts, at nearly the end of its outward movement and is compressed as in Fig. 18 and acts, after a new needle is taken and at 15 the time cam 101 frees its roller 96 to force the block 82 with pin 84 back toward the turntable carrying the tone arm to a position with the needle just over the outer record groove when the cam 94 will again act and 20 lower the sound box to permit the needle to enter said groove and the playing begins.

In the drawings the cams as shown are approximately correct, but changes in form 25 may be necessary to obtain perfect timing of the mechanism, and in order to better understand the operation thereof, it is thought advisable to describe the sequence of operations which briefly may be set forth as follows:—

30 Assuming the parts to be in the position shown in Fig. 1, which is the normal rest position at the end of a record playing operation the operations, in order, follow:—

1. Cam 94 and its co-acting mechanism 35 raises sound box and stylus.

2. Cam 101 and its co-acting mechanism swings tone arm out.

3. Cam 67 and its co-acting mechanism picks up played record.

40 4. Cam 40 and its co-acting mechanism conveys played record over well C.

5. Cam 56 and its co-acting mechanism drops played record.

6. Cam 144 and its co-acting mechanism 45 transfers new record from well D to well C.

7. Cam 67 and its co-acting mechanism picks up new record.

8. Cam 40 and its co-acting mechanism conveys new record over turntable.

50 9. Cam 56 and its co-acting mechanism drops new record on turntable.

10. Cam 94 and its co-acting mechanism drops needle in outer record groove.

11. Lug on cam 40 and its co-acting mechanism 55 lowers records in well C and raises them in D.

12. Lug on clutch member 22 acts to stop rotation of cam shaft.

It will be understood that the arms 88 and 60 110 collectively constitute a two part lever or arm and are so in effect since they are both locked by screws to a pin common to both.

The object of the trip mechanism is to 65 throw the clutch members into action to turn

the cam shaft one revolution at the end of the playing of a record and this is accomplished as follows:—

When cam 101 acts, it forces the tone arm E around to the dotted line position indicated 70 in Fig. 1 by sliding the bar 96, carrying the pin 84, to the right to the position indicated in Fig. 18, thus compressing the spring 236 which reacts when a new stylus has been picked up to return the said tone arm to the position when its sound box is over the edge of the record after which the roller 93 of cam 94 drops onto the face 134 thereof permitting the stylus to drop into or engage the outermost groove of the record and the playing starts.

The stylus in following the spiral groove of the record will gradually swing the tone arm inwardly and thus through the pin 84 will draw the slide bar 96 back to the left or toward the starting point and this back movement of the slide bar 96 by reason of its connection through bell crank 226 and link 225 with the segmental gear 179, will slowly turn the said gear on its post 181 and through the train of speed up gears 182 to 185 inclusively, the tripper supporting shaft 186 is given rapid rotation in the direction of the arrow (Fig. 27) carrying by frictional contact, the tripper 187 around with it. As the 95 said tripper swings backwardly the extension finger 194 will engage and ride up the inclined surface 199 of the arm 198 and as its movement continues it will drop off the head 202 of said arm back of and away from the path of rotary travel of the lug 219 but this lug will engage the rigid finger 196 of the tripper and swing it out of its path, after which the friction driving shaft 186 and its washer 188 will immediately swing the tripper fingers back again until finger extension 100 194 rests against the stop 233 and clear of the oncoming lug 219 when it again comes around, but the said lug will engage the rigid finger 196 again and will again swing it out 105 of its path, after which the frictional drive of shaft 186 will again swing the tripper fingers forward until the one 194 strikes the stop 233 and these oscillatory movements of the tripper are repeated over and over again 110 while the record is playing and until the stylus reaches the innermost groove of the record when the inward swing of the tone arm will cease, thus stopping the backward movement of the bar 96 and through the link 225, stopping the oscillatory movements of the segmental gear 179 as well as the tripper shaft 186. At the next rotation of the lug 219 it will, as usual again engage the rigid finger 196 and swing it back, but since the rotary 115 movement of the tripper shaft 186 has ceased, said tripper will remain in the position as left, thus leaving the lug 195 on finger 192 in the path of the lug 219 as it again comes around which will strike it and force the ex- 120

125

130

tension finger 194 against the trip lug 206 thus moving trip arm 198 around to the position indicated by dotted lines in Fig. 27 and forcing the link 222 outwardly to operate the shift lever 223 and throw the male clutch member 21 into engagement with its companion member 22 to operate the cam shaft 23 through one turn or revolution, after which the trip lugs 234 and 235 will contact and force the link 222 inwardly to reset the trip arm by reason of the lug 204 having frictional thrust yielding locking action against the leaf spring 205.

The parts are now again ready for the next 15 operation of the horn control mechanism.

What I claim and desire to secure by Letters Patent is:—

1. A phonograph mechanism having means for successively playing and interchanging 20 disk records automatically including companion wells, superposed record supporting trays in said wells, means for simultaneously dropping the trays in one well and elevating them in the other, in combination with a 25 record drum and a conveyor arm to transfer the records from and to the drum, and means for operating said mechanism.

2. In an automatic phonograph mechanism, a conveyor arm comprising a housing, 30 a pair of pivoted levers mounted therein and normally separated at one end and contacting at the other and means for spreading the contacting ends to close the opposite ends thereof for the purpose specified.

3. In an automatic disk record playing mechanism, a conveyor arm mounted to oscillate in a horizontal plane and comprising a housing, a pair of levers pivoted therein, the inner ends thereof having contact one with 40 the other, the outer ends being normally separated and provided with downward extensions having tapered terminals and shoulders to form hooks for the purpose set forth.

4. In a disk record playing mechanism, a 45 conveyor arm adapted to oscillate in a horizontal plane and comprising a housing and a pair of record engaging levers mounted to swing vertically and horizontally therein, means for operating the levers to engage and 50 release a record and means for operating the arm.

5. In a disk record playing mechanism having a turntable, a conveyor arm mounted to swing over the record turntable and comprising a housing and a pair of levers carried thereby, said levers being capable of vertical and horizontal movement, means for lifting the rear ends of the levers to cause the opposite ends thereof to engage a record, means 60 for spreading said rear ends to release the record and means for operating the arm as described.

6. In a disk record playing mechanism including a tone arm, a sound box and a casing 65 having a slot automatic tone arm control

means comprising a pin extending upwardly through said slot, an arm pivoted on said tone arm and engaging said pin means for moving the pin in one direction to swing the tone arm and for moving said pin in another 70 direction to cause said pivoted arm to raise the sound box, for the purpose specified.

7. In a disk record playing mechanism including a cabinet having a slot, a tone arm and a sound box carried thereby, a cam controlled cage, a block slidable therein and having a vertical pin projecting through the slot in the cabinet and provided at the top with a nut, a lever pivoted on the tone arm with its free end underlying said nut, means for 80 operating the lever to swing the tone arm in a horizontal plane and for raising the sound box for the purpose set forth.

8. An automatic disk record playing mechanism including a cabinet having a slot, a tone 85 arm, a sound box and sound box control comprising a pin projecting from the cabinet through said slot, a lever pivoted on the tone arm and having a slot through which said pin passes, said lever being in two parts and 90 being linked to the sound box, means for operating the lever to raise the sound box and means for operating the mechanism.

9. An automatic disk record playing mechanism including a conveyor arm having 95 record supporting hooks at its free end and an integral downwardly projected squared pin at the inner end thereof, a vertically arranged oscillating shaft provided with a socket to receive the pin in combination with means 100 for operating the playing mechanism including the shaft as described.

10. In a machine having a turntable for playing disk records and a cabinet to support and house the operative parts, a multiple 105 chamber magazine to hold the records, means for raising unplayed records in one chamber and for lowering played records into a companion chamber in step movements, means for transferring a record from the delivery 110 chamber of the magazine to the turntable and for returning it to the said companion chamber of said magazine, and means for driving the parts.

11. In a disk record playing machine having a cabinet, a turntable, a tone arm and a sound box, a multiple chamber magazine to hold the records, a power driven two-part shaft extending across said cabinet, means operating in connection with devices on said shaft for raising the records in one chamber of the magazine to the delivery level, for carrying the records to and from the turntable, for operating the tone arm and its sound box, and for lowering used records 120 in another chamber of said magazine, and means for driving said shaft.

12. In a playing machine for records having central holes, a turntable, a two-chamber magazine to hold the records, means for 130

raising said records in one chamber and for lowering them in the opposite chamber in simultaneous step movements, means for simultaneously shifting the uppermost record in one chamber and the lowermost record in the other, to respective opposite chambers, means for changing the records on the turntable and means for driving the parts.

13. In a playing machine for disk records having central openings, a turntable for playing the records, a magazine having companion chambers to hold and guide the records, means for raising records in one of the chambers and for lowering the records in the other chamber intermittently and simultaneously, means for shifting the uppermost record in one chamber and the lowermost record in the other to respective opposite chambers simultaneously, means for conveying the record last shifted at the top of the magazine to the turntable and back to the said magazine, and means for operating the parts.

14. In a playing machine for disk records having central openings, a turntable for playing the records, a magazine having companion chambers to hold and guide said records, horizontally arranged shafts at opposite sides of the magazine, star wheels on said shafts to support the records in said magazine chambers, means for shifting the uppermost record in one chamber and the lowermost record in the other to the respective opposite chambers simultaneously, means for carrying the last shifted uppermost record to the turntable and for returning it to the magazine chamber nearest said turntable, and means for operating the parts.

15. In a playing machine for disk records, a turntable, magazine chambers arranged side by side, intergeared shafts arranged at the opposite sides of the chambers, means on said shafts projecting into said chambers for supporting disk records in superposed relation therein, means for shifting records to respective opposite chambers simultaneously, means for conveying records from the magazine to the said turntable and back to the magazine and means for operating said shafts.

16. In a machine for playing disk records embodying a cabinet, a turntable, a magazine in said cabinet having a divisional wall to provide companion four walled chambers to receive the records, trays to support the records, shift arms pivotally mounted back of said chambers and adapted to engage successive trays within said chambers to shift them and their records to respective opposite chambers, and means for operating the said shift arms.

17. In a machine for playing disk records embodying a cabinet, a turntable, a magazine, trays to carry the records contained in said magazine, said magazine comprising

companion chambers each having four walls for guiding the record carrying trays, arms adapted to engage the trays and shift them to respective opposite chambers simultaneously, said arms being mounted on vertical pivots to the rear of the magazine, one arm operating over the magazine and the other operating under the same and means for actuating said arms.

18. A player for disk records including a tone arm and its sound-box and a turntable, mechanism for changing the records as they are successively presented to the turntable for playing, a two-part shaft, a clutch device to operatively connect the parts of said shaft, a trip mechanism, tone arm actuating mechanism, means for supplying the said sound-box with a new needle after the playing of each successive record, the said trip mechanism being controlled by the inward swing of the tone arm and having connection with the said tone arm actuating mechanism, said trip mechanism also being connected to the said clutch device to control the operation of the record changing mechanism, and means for driving the said shaft.

19. A player for disk records including a turntable and a tone arm, record changing mechanism to present the records to the turntable, a two-part shaft, a clutch to operatively connect the parts of said shaft, a trip mechanism including a tripper device, a spring actuated trip arm and a segmental gear adapted to drive a gear train to frictionally urge the tripper device in one direction on its shaft, tone arm actuating mechanism, a connection between a part of the trip mechanism and a part of the tone arm actuating mechanism for controlling the movement of the tripper device by the operative inward swing of the tone arm, said trip arm having connections with said clutch device to control the operation of the record changing mechanism, and means for driving the said shaft.

In testimony whereof, I have signed my name to this specification, this 6th day of June, 1925.

JOSEPH A. O'NEILL.
